CALCULATOR

Stephen G. Gould, Kirkwood, Mo., assignor to
 Missouri Portland Cement Company, St. Louis,
 Mo., a corporation of Missouri

Application September 15, 1938, Serial No. 230,053

3 Claims. (Cl. 235—89)

This invention relates generally to calculators, and particularly to calculators of a character adapted for calculating data with reference to concrete mixtures and the physical properties to be expected therefrom.

In calculators which have heretofore been proposed for determining the various characteristics and properties of concrete mixes some difficulty and confusion has been experienced among the users. For example, in determining the strength to be expected from a given concrete mixture, as for example the familiar "1-2-4" mixture, where-in to each sack of cement there is employed two cubic feet of sand and four cubic feet of coarse aggregate, the strength to be expected depends not only upon the type of cement employed, but upon the water content of the mixture. With a given type of cement the strength of a given mixture will vary inversely as the water content. In calculating concrete data, however, it is often imperative that the calculator give consideration to the consistency of the concrete mixture, and since this consideration is dependent upon the water content a factor enters which may upset the other calculations unless due account is taken. Likewise with a given concrete mix and a given consistency the strength to be expected will be different in the case of ordinary Portland cement from the case of high-early strength cement. Accordingly, difficulties have been encountered in reducing to the form of a simple calculator the data necessary for determining the physical properties to be expected from concrete, and yet take into account all of the usual variables. While efforts have heretofore been made to produce calculators of a character suitable for calculating concrete data, they have not heretofore been reduced to such form that inadvertent misreadings were not liable to be made.

The object of the present invention, generally stated, is to provide a calculator of the character referred to wherein the possibility of inadvertent misreadings is substantially obviated.

A more specific object of the present invention is to provide a calculator for concrete mixes and the properties thereof, wherein the strength of the various concrete mixes is clearly and unmistakably designated without reference to the consistency of the mix, but only with reference to the water content of the mix.

Other objects will become apparent to those skilled in the art when the following description is read in connection with the accompanying drawing, in which:

55 Figure 1 is a plan view of the front of a calcu-

lator constructed in accordance with the present invention, the slide being extended downwardly.

Figure 2 is a view similar to Figure 1 showing the reverse side of the calculator shown in Figure 1.

Figure 3 is a sectional view taken along line 3—3 of Figure 1.

In accordance with this invention, a calculator of the slide rule type is provided for determining data with reference to concrete. In view of the fact that the strength of a given concrete mix varies inversely as the water content thereof, the calculator of the present invention is arranged to indicate the strengths from concrete mixes of various water contents. In order to determine the water content of a given mix, such as a standard "1-2-4" mix, however, a series of figures is provided for indicating the quantity of water required to make such a mix stiff, medium or wet, depending upon the consistency desired. When the amount of water has thus been determined from one reading of the rule, the present invention contemplates that the rule be reset in order to read the strength corresponding to the selected water content. An especial feature of the present invention is the arrangement of characters and windows on the slide and envelope, respectively, in such manner that when the rule is being read to determine a water content, no strength can be read but that the rule must be reset in order to permit a strength reading. Likewise, when the rule is in position so that a strength reading can be made the characters for determining water content are blinded. In accordance with the embodiment illustrated in the drawing, this result is accomplished by slightly offsetting the columns of figures on one side of the slide from the columns of figures on the other side of the slide so as to require a longitudinal movement of the slide between a position where the figures on one side may be read and a position where the figures on the other side may be read.

Referring now to the drawing for an illustrative embodiment, the calculator of the present invention may comprise an envelope 1, which may be made of pyroxylin, metal, or any other suitable material, as provided. Fitted within the envelope 1 is a slide 2 arranged to slide freely back and forth through the envelope endwise. Arranged upon the front side of the envelope 1, as shown in Figure 1, is a series of windows 3, 4, 5, 6. The window 3 is arranged to cooperate with three longitudinally extending series of figures on the front surface of the slide 3 for indicating the

various standard or common cement mixes, such as the "1-1½-3" appearing in the drawing. Similarly a longitudinally extending series of figures is arranged on slide 2 to appear through window 4, and indicate the number of pounds of sand and coarse aggregate required per sack of cement for the mix shown at window 3. Likewise, a longitudinally extending series of figures visible at window 5 indicates the number of sacks of cement required to make a cubic yard of concrete and the number of cubic feet of concrete produced from one sack of cement with the mix as shown at window 3.

A further set of three series of figures extending longitudinally of slide 2 on the front thereof is visible at window 6 and indicates respectively the number of gallons of water per sack of cement required to make a concrete of the desired consistency whether stiff, medium or wet.

It will be observed that when the slide is in the position shown in Figure 1 with the figures aligned so as to be readable through the windows 3, 4, 5 and 6, the figures on the other side of the slide, as shown in Figure 2, are blinded. In order to accomplish this a plurality of windows 7, 8, 9, 10, 11, and 12 are arranged on the reverse side of envelope 1 in such manner with reference to the columns of figures on the reverse side of the slide 2 that when the figures on the front of the slide are aligned with the windows 3, 4, 5, and 6, the figures on the reverse side will not be blinded, but on the contrary, will be blinded by the windows 7, 8, 9, 10, 11, 12. In the embodiment shown in the drawing, the window 7 is arranged in alignment with the line of windows 3, 4, 5, and 6 on the front of the envelope, but the column of windows 8, 9 is displaced to the left and the column of windows 10, 11 and 12 displaced to the right of window 7, a distance corresponding to the distance between the columns of figures on the slide 2.

While in the embodiment, as shown in the drawing, the window spaces 3, 4, 5, 6, 7, 8, 9, 10, 11 and 12 are shown as perforations through the material of the envelope 1, it will be understood that an imperforate structure may be employed when the material is of such character as to permit that it be made transparent at the window spaces, but opaque elsewhere.

With this arrangement of parts when the slide is in position so as to permit a reading on the front of the device, no reading can be made on the back. This assures that when a water content is read from window 6, the reading must be transferred so as to be read at window 7, and the slide 2 actually moved within the envelope before a strength reading can be made. Data for indicating the strength of cement mixes in accordance with the water content thereof is shown at windows 8, 9, 10, 11 and 12. The windows 8 and 9 may be arranged in coordination with a pair of longitudinally extending series of figures 18 and 19 to indicate the strength of concrete mixes in which one type of cement, for example ordinary Portland, cement is employed. With cement of the high-early strength type, however, at the same water content different strengths may be expected, and consequently the longitudinally extending series of figures 20, 21, 22, 23 are arranged so as to be visible, respectively, through windows 10, 11, and 12. It will be observed that windows 8 and 9 are arranged in staggered relation with reference to windows 10, 11, and 12 so that a given longitudinal series of figures on slide 2 may be visible through but one of the windows.

With the windows and series of figures arranged in this manner, it is evident that at no time can the wrong quantity show through a given window as but one window is in line with the series of figures which concerns it. In order to more clearly distinguish between the figures which are intended to be read at windows 8 and 9 for ordinary Portland cement and the figures which are to be read at windows 10, 11, and 12 for high-early strength cement, those of series 18 and 19 may be printed in one color and those of series 20, 21, 22, 23 in another color.

In the use of the calculator of the present invention the specified mixes may be set at window 3, as for example the "1-1½-3" mix shown in the drawing. If it is desired to make this mix of a medium consistency it will be observed that five gallons of water per sack of cement will be required. Then in order to determine the strength to be expected from such a mix the slide is moved so as to set "5" at window 7. With this setting accomplished, the seven and twenty-eight days strength of such a mixture made with an ordinary Portland cement will be indicated at windows 8 and 9, respectively, and the one, two, seven and twenty-eight days strength of such a mixture made with high-early strength cement will be indicated at windows 10, 11 and 12. It is frequently desired to work backwards from a required strength and to determine not only the consistency, but the mix necessary to give a required strength. In such case the required strength may be set at window 9, for instance, the number of gallons of water corresponding to that strength read at window 7, the rule reversed and the slide manipulated, so as to locate the water value just read from window 7, in position in window 6 corresponding to the desired consistency. When this setting is accomplished reference to window 3 will indicate the mix to be employed.

The arrangement of the figures on the opposite sides of the slide in such coordination with their respective windows as to obscure or interfere with proper reading of the slide on one side, when it is set for reading on the other side, minimizes the likelihood of making misreadings from the device, and also reduces the number of windows which would otherwise be necessary, and which if present would also contribute to the likelihood of misreadings. Since for each different water content of the concrete mixture a total of six "strength" readings are available, and since for each different mix three different water contents are available, confusion would occur if the "strength" readings appeared automatically upon setting the device for a given mix. In the arrangement disclosed, however, a resetting of the device is compelled before the "strength" corresponding to any given mix may be ascertained, and since the resetting is compulsory, there is less likelihood that the wrong water content will be selected than if the "strength" might be read without resetting the device.

From the foregoing description it should appear that the present invention accomplishes its objects and that a highly practical concrete calculator is provided which may be manipulated in a facile and convenient manner without liability to inadvertent misreadings. While in the foregoing description reference has been made to various details of the device, and especially to the fact that the squares and windows are arranged with such reference to each other that when the rule is set for reading on its

front, it cannot be read on its reverse side, and it is also pointed out that this result could be accomplished by offsetting the columns of figures on the back from the corresponding columns 5 of figures on the front, it is evident, of course, that the same result could be accomplished with the columns on the front and back of the slide in alinement, but with the windows in the envelope mutually offset. Other comparable 10 arrangements and reversal of parts may be made within the spirit of the invention by those skilled in the art. It is to be distinctly understood, therefore, that such modifications, rearrangements, and adaptations of the features of the 15 calculator hereinbefore described, as do not depart from the spirit of this invention are, although not specifically described herein, contemplated by and within the scope of the appended claims.

20 Having thus described the invention, what is claimed is:

1. A calculator of the kind described, comprising, an envelope having windows in opposite sides thereof, a slide movable in said envelope 25 and having characters on both sides thereof arranged to be read through the windows in said envelope, the windows and characters on one side being so positioned relative to the windows

and characters on the opposite side that when the characters of the slide are alined with the windows on one side they are disaligned with the windows on the opposite side of the envelope.

2. A calculator of the kind described, comprising, an envelope having windows in opposite sides thereof, a slide movable in said envelope and having a plurality of columns of figures arranged on both sides thereof for selective reading through the windows, said columns of figures on the slide 10 being transversely disaligned front and back so as to compel resetting of the slide between readings on the opposite sides thereof and the windows on opposite sides of the envelope being so positioned with respect to the columns of figures on 15 the respective sides of the slide as to interfere with proper reading of the figures on one side when those on the other side are alined with their corresponding windows.

3. A calculator for concrete mixes comprising, 20 a slide having a plurality of longitudinally extending scales on each side, and an envelope having windows arranged to cooperate one with each scale, the windows on the respective sides being arranged so as to interfere with proper 25 reading the scales on one side when those on the other side are readable.
